UNITED STATES PATENT OFFICE.

ROBERT F. WILSON, OF SAN FRANCISCO, CALIFORNIA, ASSIGNOR TO SOUTHERN PACIFIC COMPANY, OF ANCHORAGE, KENTUCKY, A CORPORATION OF KENTUCKY.

DESIGN FOR AN EMBLEM.

49,840.

Specification for Design.

Patented Oct. 31, 1916.

Application filed November 20, 1915. Serial No. 62,658. Term of patent 14 years.

To all whom it may concern:

Be it known that I, ROBERT F. WILSON, a citizen of the United States, residing in the city and county of San Francisco and State of California, have invented a new, original, and ornamental Design for an Emblem, of which the following is a specification.

Referring to the accompanying drawing the figure is a plan view of an emblem showing my new design.

I claim:—

The ornamental design for an emblem, as shown.

In testimony whereof I have signed my name to this specification in the presence of two subscribing witnesses.

ROBERT F. WILSON.

Witnesses:

H. C. TIBBITS,
E. J. FOULS.
